UNITED STATES PATENT OFFICE.

HENRY HABERMANN, OF NEW YORK, N. Y., ASSIGNOR, BY MESNE ASSIGNMENTS, TO
THE ATLAS-GLOBE CHINA CO., OF NILES, OHIO, A CORPORATION OF OHIO.

DESIGN FOR A DECALCOMANIA STRIP FOR A DINNER PLATE OR SIMILAR ARTICLE.

Application filed March 6, 1923. Serial No. 5,372. Term of patent 7 years.

To all whom it may concern:

Be it known that I, HENRY HABERMANN, a citizen of the United States, and resident of the borough and county of Bronx, city and State of New York, have invented a new, original, and ornamental Design for a Decalcomania Strip for a Dinner Plate or Similar Article, of which the following is a specification.

The figure is a face view of a decalcomania strip, showing my new design, the outline of the strip being indicated by dotted lines.

I claim:

The ornamental design for a decalcomania strip for a dinner plate or similar article as shown and described.

HENRY HABERMANN.
